(57) **CLAIM**

The ornamental design for a cycling accessory holder, as shown and described.

DESCRIPTION

FIG. 1 is a front perspective view of a cycling accessory holder showing our new design;

FIG. 2 is a rear, lower perspective view thereof;

FIG. 3 is a rear, upper perspective view thereof;

FIG. 4 is a front view thereof;

FIG. 5 is a rear view thereof;

FIG. 6 is a right side view thereof;

FIG. 7 is a left side view thereof;

FIG. 8 is top view thereof;

FIG. 9 is a bottom view thereof;

FIG. 10 is an environmental, perspective view thereof; and,

FIG. 11 is an environmental, perspective view thereof. The broken lines shown in FIGS. 10 and 11, illustrate environment that form no part of the claimed design.
